(57) **CLAIM**

The ornamental design for a foldable solar panel, as shown and described.

DESCRIPTION

FIG. 1 is a top, left and front side perspective view of a foldable solar panel, showing my new design;

FIG. 2 is a top, right and back side perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof;

FIG. 8 is a back elevational view thereof;

FIG. 9 is an enlarged view of the portion framed in FIG. 2;

FIG. 10 is an enlarged view of the portion framed in FIG. 3;

FIG. 11 is an enlarged view of the portion framed in FIG. 5;

and,

FIG. 12 is an enlarged view of the portion framed in FIG. 8.

1 Claim, 8 Drawing Sheets
